PHARMACEUTICAL

Ferdinand W. Nitardy, Brooklyn, N. Y., and
Walter G. Christiansen, Glen Ridge, N. J., as-
signors to E. R. Squibb & Sons, New York,
N. Y., a corporation of New York

No Drawing. Application December 4, 1937,
Serial No. 178,132

9 Claims. (Cl. 167—58)

This invention relates to inhalants, i. e., preparations for nasal administration, as by dropping or spraying.

Heretofore, oil-soluble inhalant medicinal agents (e. g., ephedrine) have been incorporated in mineral-oil vehicles for the production of inhalants. Numerous cases of lipid pneumonia have resulted from the use of such preparations, apparently because of the non-absorption of oil 10 vehicle finding its way into the alveoli of the lung.

It is the object of this invention to provide non-injurious inhalants; more particularly, to provide preparations of oil-soluble inhalant medicinal agents embodying a vehicle absorbable by the lungs.

It has been found that certain oily aliphatic esters are absorbable by the body and constitute effective vehicles for oil-soluble inhalant medicinal agents. In the event these absorbable oily aliphatic esters enter the lung, they do not remain there, either because of their tendency to pass into water solution or because of their susceptibility to enzyme hydrolysis. Moreover, the slight water-solubility of some of these esters enhances the effectiveness of the medicinal agents, since aqueous fluids are present in the nasal passages.

The following esters, inter alia, have been 30 found to be absorbable effective vehicles:

Ethyl oleate.
Iso-butyl laurate.
Ethyl stearate.
Butyl palmitate.
35 Glycol mono-oleate.
Glycerol mono-oleate.
Mannitol mono-oleate.
Diglycol mono-laurate.
Ethyl esters of the mixtures of fatty acids deriv-
40 able from olive oil, coconut oil, or linseed oil.
Glycol mono-ester of linseed oil fatty acids.
Glycerol mono-ester of linseed oil fatty acids.

Aliphatic polyhydroxy compounds completely 45 esterified with higher fatty acids, such as glyceryl trioleate, remain unabsorbed in the lung. The absorbable vehicles specifically disclosed belong to the group consisting of lower-alkyl esters of higher fatty acids and aliphatic polyhydroxy 50 compounds partially esterified with higher fatty acids.

These absorbable vehicles are effective for all inhalants embodying oil-soluble medicinal agents. The following examples are illustrative of the application of this invention to plain and com-

pound ephedrine inhalants and to non-ephedrine inhalants.

Example 1

A plain ephedrine inhalant is made by incor- 5 porating 1.5 g. ephedrine in 148.5 g. ethyl oleate.

Example 2

A compound ephedrine inhalant is made by incorporating the following in 144.0 g. ethyl 10 oleate:

	Grams
Ephedrine	1.5
Phenol	1.1
Menthol	1.1
Camphor	1.1
Oil of thyme	0.4
Oil of lilac	0.1

Example 3

A non-ephedrine inhalant is made by incor- 20 porating the following in 144.0 g. ethyl oleate:

	Grams
Phenol	1.1
Menthol	1.1
Camphor	1.1
Oil of thyme	0.4
Oil of lilac	0.1

Example 4

An inhalant is made by incorporating β -phenethyl amine, β -phenyl-isopropylamine, m (or p)-hydroxy- α -(methylaminomethyl)-benzyl alcohol, or the like—in ethyl oleate.

Example 5

β -phenethyl amine or a medicinal derivative thereof is incorporated in the compound inhalant preparation of Example 2 in place of ephedrine.

In the compound inhalants, a variety of substances can be used instead of the phenol, camphor, menthol, oil of thyme, and oil of lilac. Menthol and camphor are employed to relieve congestion, and oil of thyme and oil of lilac to improve the odor of the product; and these may be replaced by other similarly effective agents. The phenol is used because of its anesthetic and antiseptic properties, and may be replaced by anesthetics such as benzyl alcohol, saligenin, chlorobutanol, or the alkyl esters of para-amino- 40 benzoic acid, and/or by antiseptics such as hydroxy-quinoline, chlor-hydroxy-quinoline, or ethyl butyl resorcinol.

When the inhalant is unsatisfactory because of 45 excessive viscosity of the vehicle, adjustment can 50 55

be made by replacing part of the viscous vehicle with ethyl oleate. Conversely, if the ethyl oleate preparations are too thin, this vehicle may be partly replaced with one having a higher viscosity.

5 The invention may be variously otherwise embodied within the scope of the appended claims.

We claim:

1. An inhalant essentially comprising an oil-soluble inhalant medicinal agent and a lung-absorbable vehicle of the group consisting of lower-alkyl esters of higher fatty acids and aliphatic polyhydroxy compounds incompletely esterified with higher fatty acids.
- 10 2. An inhalant essentially comprising an oil-soluble inhalant medicinal agent and a lung-absorbable oily aliphatic mono-ester of a higher fatty acid.
- 15 3. An inhalant essentially comprising an oil-soluble inhalant medicinal agent and a lung-
- 20

absorbable oily aliphatic mono-ester of a higher unsaturated fatty acid.

4. An inhalant essentially comprising an oil-soluble inhalant medicinal agent and ethyl oleate.

5. An inhalant essentially comprising an oil-soluble inhalant medicinal agent and an ethyl ester of the mixture of fatty acids derivable from an oil of the group consisting of olive oil, coconut oil, and linseed oil.

6. An inhalant essentially comprising an oil-soluble inhalant medicinal agent and glyceryl mono-oleate.

7. An inhalant essentially comprising ephedrine and ethyl oleate.

8. An inhalant essentially comprising phenol, 15 menthol, camphor, and ethyl oleate.

9. A medicinal inhalant preparation essentially comprising β -phenethylamine and ethyl oleate.

FERDINAND W. NITARDY.
